SLICING MACHINE

Henry Yerkey, Galesburg, Ill.

Application November 23, 1931, Serial No. 576,680

8 Claims. (Cl. 146—100)

The present invention relates to slicing machines and more particularly to such as are capable of being used for the slicing of a plurality of commodities, either simultaneously or selectively.

3 Among the objects of this invention are to provide a machine of the character indicated in which a single cutting blade may be simultaneously or selectively used for the cutting of different commodities, such as bread and bacon; to 10 provide a construction of the nature indicated which may be modified in its operation, by two or three slight adjustments, so as to shift its cutting from one to the other of two commodities or may be set to cut both of them simultaneously; 15 to provide a structure of the character indicated which may be adjusted so as to vary the thickness of the slice cut as desired; to provide a structure of the character indicated which will simultaneously slice bacon and remove the rind therefrom; to provide a structure of the character indicated which will slice bacon and its rind and simultaneously remove the rind from the slices; to provide a machine of the character indicated which may be operated either manually or by a 20 motor and which is readily convertible from one mode of operation to the other; and such further objects, advantages and capabilities as will hereafter appear and as are inherent in the construction disclosed herein. My invention further resides in the combination, construction and arrangement of parts illustrated in the accompanying drawings and, while I have shown therein what is now considered the preferred embodiment of this invention, I desire the same to be 25 understood as illustrative only and not to be interpreted in a limiting sense.

In the drawings annexed hereto and forming a part hereof,

40 Fig. 1 is a plan view of my machine with parts thereof broken away;

Fig. 2 is an end elevation of this construction;

Fig. 3 is a side elevation of the structure shown in Fig. 2, looking at the right hand side of this figure;

45 Fig. 4 is a broken transverse section taken approximately along the plane indicated by the line 4—4, Fig. 3;

Fig. 5 is a transverse section taken approximately along the plane indicated by the line 5—5, Fig. 3;

50 Fig. 6 is a transverse section taken approximately along the plane indicated by the line 6—6, Fig. 5;

55 Fig. 7 is a fragmentary transverse section

taken approximately along the plane indicated by the line 7—7, Fig. 5;

Fig. 8 is an elevation of the form of cutting blade preferred for use in my new machine.

Reference will now be made in greater detail to the annexed drawings wherein the structure is shown as comprising a pair of end frames 1 and 2 having legs 3 and a body member 4 connecting the ends, the ends being held together by means of a plurality of rods 5, which draw the ends of the body member 4 into suitable grooves formed in the inner faces of the frame members 1 and 2. The lateral edges of the body member, which is of sheet material, are rolled over as indicated at 6 and 7, the roll 6 surrounding one 10 of the tie rods 5 and the other one rising above a shelf 8 to serve as a lateral guide for a loaf of bread or the like resting upon said shelf. The edge of the shelf 8 is turned upwardly, as indicated at 9, and also assists in guiding the bread 15 and holding same in place.

20 A drive shaft 10 extends axially through the machine and connects the cutting blade 11 in driving relation with the driving mechanism at the opposite end of the machine. This driving mechanism comprises a plate 12 having a flange 13 formed integrally therewith and a suitable gear 14, either secured to the plate or formed integrally therewith. The driving mechanism 25 also includes the bevel gear 15, shaft 16 and crank 17 or motor 18. As a matter of fact, both crank and motor will be supplied, at least in some of the machines, so that the motor may be used when considerable cutting is to be done or the crank 30 may be used when only one or two slices are to be cut. Of course the operator is not limited as 35 the number of slices which are cut by hand and he may use either the crank or the motor, as most suits his fancy. The crank is illustrated in 40 Figs. 1, 2 and 3 as being provided with a ratchet mechanism 19 which will permit the shaft 16 to be driven by the motor 18 without turning the crank 17. While the drive train between the motor 18 and shaft 16 is not shown as being 45 equipped with a ratchet mechanism similar to mechanism 19, it will be understood that such a mechanism may be inserted at any convenient location in this drive train without departing from the spirit of this invention. A bracket 20 secured to the end frame 1 serves to support the shaft 16 and furnish bearings therefor. The housing 21 encases the worm 22 and worm wheel 23 and is mounted upon a bracket 24 secured to 50

55

the adjacent leg 3 of the machine. The motor 18 is similarly mounted.

Sprockets 25 and 26 are mounted upon shafts 16 and 28 and are connected by the sprocket chain 5 27 to furnish driving connection between the motor 18 and shaft 10.

Brackets 30 (see Fig. 2) are formed integral with the end frames and a guide plate 31 is mounted upon these brackets. This guide plate 10 is adapted to be engaged by the edge of a slab of bacon placed in the machine and serves to guide the same straight ahead and prevent it from being moved laterally by the knife during its cutting operation.

15 A pair of shafts 32 and 33 are provided with coarse threads, as shown in Fig. 3, and have fixedly mounted thereon within the flange 13 the gears 34 and 35. A series of perforations 36 are formed in the flange 13 and have plungers 20 37 mounted therein, which plungers are adapted to serve as gear teeth to mesh with the gears 34 and 35, as shown in Fig. 5. The plungers 37 have arms 38 extending laterally therefrom, as shown in Fig. 6, and these arms are engaged by springs 25 39 which force them out against the inner face of the ring 40. This ring has an enlargement upon its inner face which serves as a cam to push the plungers 37 out so that they will engage the gears 34 and 35. As will be evident from 30 Fig. 5, the function of the gears 34, 35 and plungers 37 is to give intermittent rotation to the shafts 32 and 33. This is done in order to intermittently advance the bread, bacon or other product which is being sliced.

35 Blocks 42 and 43 are mounted upon the shafts 32 and 33 and cooperate therewith in advancing the product being sliced toward cutting position. The block 42 has a channel 44 therein which receives the screw 32. A housing 45 is 40 mounted on top of the block 42 and has a block 46 therein which is cut on its lower face with suitable threads to mesh with the threads of the screw 32. A leaf spring 47 is held down by a suitable rod or the like 48 extending through 45 the casing 45. This spring exerts downward pressure upon the block 46 to hold it into engagement with the screw 32. A cam 49 is mounted upon a rod 50 which rotates about its longitudinal axis to lift the block 46 out of engagement 50 with the screw 32. When the handle 51 occupies the position shown in Fig. 1, the threads on the under side of block 46 are in engagement with the threads of the screw 32. In this position, block 42 will be intermittently advanced as 55 screw 32 is intermittently turned.

Block 43 is constructed similarly to block 42 and has a shaft 50 extending into same for the operation of a threaded block similar to block 46. The shaft 50 also has a handle 51 for operation thereof. In these respects the two constructions are similar.

Extending diagonally through block 42 are a 60 pair of rods 53 connected adjacent their ends by cross heads 54 and 55. The former of these 65 serves as a handle whereby the rods may be pulled or pushed through the block 42, while the latter carries pointed pins adapted to engage the meat resting upon the bottom or body member 4. It will therefore be seen that, in 70 order to place a piece of meat upon the tray or bottom 4, the cross head 54 is raised and this pulls the pins 56 up far enough so that the meat can be put into place. After this is done, the block 42 is adjusted longitudinally of the screw 75 32 until the block 55 is properly positioned

lengthwise of the machine. The cross head 54 is then pushed down to cause the pins 56 to engage the meat. The handle 51 is then manipulated to turn the shaft 50 in the right direction to cause release of block 46 so that its threads 5 may engage the screw 32. After this has been done, the shaft 16 may be caused to rotate and this will cause operation of the machine. This causes functioning of the blade 11 and intermittent rotation of shaft 32. The latter results 10 in intermittent forward actuation of the meat.

An arm 58 extends laterally from the block 43 and is connected adjacent its extremity with a plate 59 carrying a plurality of pins 60. These are designed to be engaged by the commodity 15 which is to be sliced at this side of the machine. This is intended primarily for the slicing of bread or the like. While it is intended that a loaf of bread shall be impaled upon the pins 60, it will be understood that this is not essential 20 as the bread may be put down upon the shelf 8 in front of the slide 59, if desired.

An arm 61 extends into a perforation in a lug 63, while an arm 62 extends into a longitudinal aperture in the shaft 10. These arms support 25 a tray 64 upon which the sliced bread collects after passing out of the machine. Rods 65 extend through the end frame of the machine and are connected together outside thereof by means of a cross head 66. Stops 65a are preferably 30 mounted upon two or more of the rods 65 to serve as means for limiting the outward motion of this carrying rack. As the sliced meat is cut and pushed outwardly, it presses against the cross head 66 and shoves that away from the 35 machine frame. The outward pushing of the machine and the inherent resistance of the tray tend to keep the meat slices arranged in a suitable condition and ready to be handled.

Plates 67 are secured to the end frame member 2 in any suitable manner and cover that part of the opening through this frame member which is not utilized in the slicing operations. These plates have a tendency to keep the operator from getting his hand in front of the cutting blade as it rotates during the slicing operation. Bars 68 and 69 constitute a part of the end frame member 2 and are integral with the outer substantially circular part thereof. Centrally arranged with relation to this ring and 45 integral with the inner ends of the bars 68 and 69 is a disc 70 which furnishes bearing for one end of each of the shafts 32 and 33. A comparable disc 71, at the opposite end of the machine, furnishes bearings for the remaining ends 50 of these shafts. Suitable bearing elements may be mounted in these discs to furnish proper 55 wearing surface for the shafts.

A small knife blade 72 is secured to or formed integrally with the blade 11 and projects laterally therefrom to serve as a trimming knife for removing the rind from bacon when slicing the same. This knife describes a cylindrical path in its travel about the shaft 10. The latter may be centrally arranged with relation to the 60 circular frame member or it may be slightly eccentric with relation thereto. If it is mounted eccentrically with relation to this frame member, the lower part of the path of the knife 72 should be spaced upwardly from the inner face 65 of the frame member to accommodate the thickness of the rind between the frame member and the knife. The upper portion of the course of travel of this knife may be substantially coincident with the inner face of the upper part of 70 75

this ring. If the knife 72 travels concentrically with relation to the ring, its path of travel will be spaced all the way around the same as at the bottom part of its course of travel; that is, 5 far enough inwardly to accommodate the thickness of the rind.

Pivotedly connected at 73 with the member 75 is an extension 74 of the blade 11. Member 75 is, in reality, a pair of similar plates secured to the 10 extremity of the blade 11 and the extension 74 is pivoted to swing between these plates. A blade actuating member 76 is pivoted at 77 to member 75 and has a part 80 which swings in a notch 78. In the position illustrated in Fig. 2, 15 this member holds the knife blade extension 74 outwardly so as to be substantially in contact with the end member 2. Since the inner portion of this frame member extends inwardly somewhat as indicated at 79, it will hold the 20 meat up so that the extension 74 will be sure to cut through the same. When the actuating member 76 is turned about its pivot 77 so that the part 80 engages the upstanding lug on the inward end of the blade 74, this latter will be 25 turned about its pivot 73 and it will be raised up to a point such that this blade will not cut through the rind. Therefore, the blade 11 will slice bacon, blade 72 will remove the rind therefrom, but blade 74 will not cut the rind into 30 strips, as it will do when turned down into the position illustrated in Fig. 2. Points 81 project inwardly very slightly from the ring and thus tend to hold the meat in place when the 35 knife is going through same.

Reference has been made to the ring 40 rotating with respect to the flange 13 for the purpose of pushing the plungers 37 out into position to act as gear teeth in rotating the gear 35. Reference is made to the fact that a groove is cut in 40 the flange 13 to receive the ring 40 and also to the fact that this ring is severed, as indicated at 45 82. The ends of the ring are connected by a plate 83 which is secured to the ends by means of screws or their equivalents 84. This plate 83 has a finger piece 85 turned up and formed upon one edge thereof and this serves as a means for rotating the ring in the groove in flange 13. Upon one 50 edge of the plate is formed an indicator point 86 which cooperates with the index marks 87 upon the flange 13 on disc 12. Similar index 55 marks may, if desired, be placed upon the flat face of the disc 12, adjacent the marks 87, and numerals may be added to indicate, for convenience, the thickness of the slice or something 60 which may be translated into such thickness. It will be understood that by grasping the finger piece 85 and rotating the ring 40 about the flange 13 a greater or fewer number of the plungers or gear teeth 37 will be caused to be projected inwardly to cause rotation of the gears 34 and 35. Also, the greater the distance these gears rotate, 65 the greater will be the thickness of the slices cut. In order to limit the amount which the ring 40 may rotate, pins 90 and 91 are rigidly mounted in the flange 13 and it will therefore be seen that the ends of the cam on the inner surface of the ring 40 will abut against these pins, thus stopping further rotation of the ring.

In place of the blade 11, shown in Fig. 2 of the 70 drawings, I prefer to use the blade shown in detail in Fig. 8 thereof. This blade is mounted on the shaft 10 in any suitable manner. In Fig. 8, the collar 92 and set screw 93 have been omitted for the sake of simplifying the drawing.

75 The support 11a does not have a cutting edge,

as does the blade 11, but is provided with a plurality of blades 94 and 95 which may be beveled to a cutting edge on either or both faces. These blades may be secured to the support 11a by suitable means, such as rivets. The blade 94 is made somewhat larger than the blades 95 because the latter are rather too small for use in the position occupied by the blade 94. The reason for using the smaller blades 94 and 95 is that these can be held and given the necessary temper with much less danger of warping than a blade of the size of 11. Therefore, a cutting means of the character illustrated in Fig. 8 is much easier and cheaper to make than one of the other type.

The blade 74a is slightly different in shape 15 than the blade 74 but is pivoted at 73 in the same manner as the blade 74. The plates 75 and 75a are somewhat different in form but serve the same purpose in serving as supporting means for the pivoted blade 74a. The plate 75b is somewhat 20 larger than the plate 75a and carries on its outer extremity the rind trimming knife 72 which projects laterally into a position to remove the rind from the meat. The knife 74a, in the position shown in Fig. 8, will not cut beyond the point 25 reached by the last knife 95. However, when the actuating member 76a is shoved inwardly, the projection 80a engages the projection on the end of the blade 74a and forces this outwardly 30 away from the support 11a, turning the cutting edge of the blade 74a farther away from the shaft end. Therefore, this blade cuts through the rind of the meat, severing it from the rind of the un-sliced portion. The end of the actuating member 35 76a is provided with a hook 96 which engages the projection on the end of the blade. However, in view of the provision of the slot 97 and the pin 98, the projection 96 may be dispensed with if desired. The slot 97 and pin 98 may be dispensed with by suitable construction of the device which 40 will prevent the member 76a from being withdrawn by member 74a being turned about its pivot 73 so as to release the hook 96.

It is of course understood that the specific 45 description of structure set forth above may be departed from without departing from the spirit of this invention as set forth in this specification and the appended claims.

Having now described my invention, I claim:

1. In a slicing machine, a frame-work, fixed 50 supporting means to support a plurality of products to be sliced, a rotary slicing knife, a rotatable shaft supporting and actuating said knife, actuating means for said shaft, shafts actuating the products into slicing position, means actuated by the last mentioned shafts to transmit motion therefrom to the products to cause same to be advanced, means for selectively or simultaneously advancing the last mentioned means to advance one or another of the products being sliced, and a trimming knife projecting laterally from the slicing knife adjacent the outer end of the latter, the supporting means for the product to be sliced being located outwardly beyond the end of the slicing knife and at such a point that it will hold the product in such a position that the trimming knife will cut just inside of the rind of the meat, when same is being sliced, to remove the rind from the meat.

2. In a slicing machine, a frame-work, fixed 70 supporting means to support a plurality of products to be sliced, a rotary slicing knife, a rotatable shaft supporting and actuating said knife, actuating means for said shaft, shafts actuating the products into slicing position, means actuated 75

- by the last mentioned shafts to transmit motion therefrom to the products to cause same to be advanced, and means for selectively or simultaneously advancing the last mentioned means to 5 advance one or another of the products being sliced, in which one of the product supporting means is partially cylindrical and is located coaxially with relation to the knife-supporting shaft and in which the slicing knife extends outwardly to a distance less than the outer surface 10 of the meat rind supported on said cylindrical supporting means and has an auxiliary knife which may be turned into a position to cut entirely through the meat rind.
- 15 3. In a slicing machine, a shaft, a slicing knife having a rigid body portion and an extension connected adjacent the outer extremity thereof, said extension being mounted for pivotal motion in the plane of the body portion, said knife being 20 rigidly secured to said shaft and rotated thereby to slice a product which it is desired to have sliced and the extension when turned into operative position, serving to increase the effective cutting length of the main portion of the slicing 25 knife.
4. A structure as defined by claim 3 in which the slicing blade is provided with handled means for holding the auxiliary blade out in cutting position or drawing the same into inoperative position.
- 30 5. In a slicing machine, a rotary slicing knife, a shaft carrying and rotating said knife, a plurality of threaded shafts adjacent the first mentioned shaft for intermittently advancing articles 35 to be sliced into the path of the slicing knife, means attached to the first mentioned shaft for rotating the same, said means having a flange directed toward the slicing knife, said flange having a plurality of perforations extending therethrough and spaced around a portion of its 40 periphery, plungers mounted in said perforations and movable therein to be extended beyond either the inner or outer face of the flange and

adapted in one position to serve as gear teeth, gears mounted upon and secured to said plurality of shafts and adapted to coöperate with the plungers extending through the flange, and means for actuating one or more of said plungers into a position to coöperate with said gears.

6. A structure as defined by claim 5 in which the means for actuating the plungers comprises a ring mounted on said flange and rotatable thereabout, said ring having upon its inner face 10 a cam portion to coöperate with said plungers in causing same to be moved through said flange.

7. In a slicing machine, a slicing member comprising a flat body part having its outer periphery curved and extending from a point near the axis of rotation to a point remote therefrom, said flat supporting member having cutting blades mounted thereon so that each successive blade cuts a greater distance from the axis of rotation than its predecessors, said slicing member having 15 at its outer extremity an auxiliary blade pivoted to be actuated from a position in which it will not cut farther out than the first mentioned blades to a position in which it will cut beyond the limit of the other blades.

8. In a slicing machine, a rotary slicing member comprising a flat body part having its outer periphery curved and extending from a point near the axis of rotation of the slicing member to a point remote therefrom, said flat body part 30 having cutting blades mounted thereon so that each successive blade cuts a greater distance from the axis of rotation than its predecessors, said supporting member having at its outer extremity a trimming blade extending at approximately a 35 right angle to the plane of the body part for removing rind from sliced meat, in combination with meat supporting means spaced a distance from the axis of rotation of the slicing member which is just sufficient to permit the trimming blade 40 to cut inside of the meat rind.

HENRY YERKEY.
